(57) **CLAIM**

The ornamental design for a child safety device, as shown and described.

DESCRIPTION

FIG. 1 is a perspective view of a child safety device according to the present invention as seen from the front, top and left side thereof;

FIG. 2 is another perspective view of the design according to the present invention as seen from the front, top and right side thereof, with a portion thereof shown in a pivoted position;

FIG. 3 is a view similar to FIG. 2, but the portion shown in a completely pivoted position and forming an enclosure of the child safety device;

FIG. 4 is an end view of the child safety device seen from the rear and with the portion pivoted to the position of FIG. 1; and

FIG. 5 is a bottom view of the child safety device;

FIG. 6 is a perspective view similar to FIG. 1 of a second embodiment of a child safety device according to the present invention, showing a portion thereof in a partly open pivoted position;

FIG. 7 is an end view from the left side of the embodiment of FIG. 6;

FIG. 8 is a top view of the embodiment of FIG. 6;

FIG. 9 is a perspective view showing the second embodiment with the portion in a closed position;

FIG. 10 is a left end view of the second embodiment as shown in FIG. 9;

FIG. 11 is a top view of the second embodiment as shown in FIG. 9;

FIG. 12 is a perspective view showing the portion in a completely open position;

FIG. 13 is a left end view of the second embodiment as shown in FIG. 12; and,

FIG. 14 is a top view of the second embodiment as illustrated in FIG. 12.
